(57) **CLAIM**

The ornamental design for a baby safety gate, as shown and described.

DESCRIPTION

FIG. 1 is a top, front, left side perspective view of a baby safety gate, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom, rear, right side perspective view thereof;

FIG. 9 is a top, front, left side perspective view of the baby safety gate in closing state;

FIG. 10 is an enlarged view of a portion indicated in FIG. 8; and,

FIG. 11 is an enlarged view thereof.

The broken lines in the drawing depict environmental subject matter only and form no part of the claimed design. The dash dot dash lines in FIGS. 8, 10 and 11 are for the purpose of depicting the cut line of the enlarged view and form no part of the claim.
